COSMETIC CREAM JAR

Samuel F. Perkins, Jr., Washington, D. C.
Application April 9, 1948, Serial No. 145,607

Term of patent 14 years

(Cl. D58—25)

To all whom it may concern:

Be it known that I, Samuel F. Perkins, Jr., a citizen of the United States, residing in Washington, D. C., have invented a new, original, and ornamental Design for a Cosmetic Cream Jar, of which the following is a specification, reference being had to the accompanying drawing, forming part thereof.

The figure on the drawing is a side perspective view of a cosmetic cream jar showing my new design.

The side of the jar not shown presents a substantially similar appearance as the side shown.

I claim:

The ornamental design for a cosmetic cream jar, as shown and described.

SAMUEL F. PERKINS, JR.
